UNITED STATES PATENT OFFICE.

GLENNIE V. PATTERSON, OF BROWNWOOD, TEXAS.

DESIGN FOR A WATCH-CHARM, PIN, OR SIMILAR ARTICLE.

48,758.

Specification for Design.

Patented Mar. 21, 1916.

Application filed January 4, 1916. Serial No. 70,300. Term of patent 7 years.

To all whom it may concern:

Be it known that I, GLENNIE V. PATTERSON, a citizen of the United States of America, residing at Brownwood, in the county of Brown and State of Texas, have invented a new, original, and ornamental Design for Watch-Charms, Pins, or Similar Articles, of which the following is a

specification, reference being had to the accompanying drawing, forming part hereof.

The figure is a plan view of a watch charm showing my new design.

I claim:

The ornamental design for a watch charm, pin or similar articles, as shown.

GLENNIE V. PATTERSON. [L.S.]
